REMOTE CONTROL MECHANISM

Filed Sept. 12, 1931

FIG. 3

FIG. 2

FIG. 1

FIG. 4

UNITED STATES PATENT OFFICE

RUSSELL G. THOMPSON, OF ROCHESTER, NEW YORK, ASSIGNOR TO ELECTROMATIC TYPEWRITERS, INC., OF ROCHESTER, NEW YORK, A CORPORATION OF NEW YORK

REMOTE CONTROL MECHANISM

Application filed September 12, 1931. Serial No. 562,521.

This invention relates to improvements in remote control mechanism, and has for its principal object the provision of simple and inexpensive means for selectively controlling 5 the operation of a plurality of transmitting switches by means of a perforated master sheet.

Another object of the invention is the provision of a power driven roller and a plurality of star wheels cooperating therewith, each 10 of the star wheels being arranged to operate a switch, and a master sheet adapted to be arranged on the power driven roller for selectively controlling the operation of the star 15 wheels thereby.

Still another object of the invention is the provision of a star wheel of a form adapted 20 to close its switch when operated and maintain it closed a predetermined interval of time or until operated a second time by the power driven roller.

To these and other ends, the invention consists in the construction and arrangement of 25 parts that will appear from the following description when read in conjunction with the accompanying drawing the novel features being pointed out in the claims at the end of the specification.

In the drawing:

30 Fig. 1 is a transverse section showing so much of a remote control mechanism as is necessary to illustrate one application of the invention, the section being taken substantially on line 1—1 of Fig. 4 and looking in the direction of the arrows at said line;

35 Fig. 2 is a similar section taken substantially on line 2—2 of Fig. 4 and looking in the direction of the arrow at said line;

40 Fig. 3 is a view similar to Fig. 2 but showing the star wheel in another position, and

Fig. 4 is a fragmentary plan view of the mechanism.

45 Referring particularly to the drawing, the device illustrated comprises a switch having resilient arms 1 and 2 rigidly mounted in a support 3 and insulated from each other. This switch is comprised in a circuit 4 which may be connected with a remote receiving apparatus of any usual or preferred form 50 adapted to convert electrical impulses into

intelligible form. The arms 1 and 2 are normally free from each other to break the circuit or normally maintain it open, means being provided, however, for flexing the arm 2 into engagement with the arm 1 or a contact 55 point 5 thereon to close the circuit. To this end, a resilient arm 6 is mounted on the support 3 and projects therefrom in the vertical plane of the arms 1 and 2 and adjacent the arm 2 but insulated therefrom in spaced relation thereto. At its free end, the arm 6 is operatively connected with the arm 2 by means of an insulating block 7.

Power actuated means are provided for actuating the arm 6 to close the circuit. Said 60 means comprises an actuator in the form of a lever 8 mounted on a common pivot rod 9 and normally arranged in contact with the arm 6 at or adjacent its rear end. At its forward end, a star wheel 11 is revolvably mounted thereon adjacent the surface of a power driven roller 12. The roller 12 is provided with longitudinally arranged depressions 13 forming projections 14 between them, with which the arms 15 of the star wheels 11 are 65 adapted to engage to turn the star wheels on the levers 8, which operation cams the forward end of the lever away from the roller and causes its rear end to flex the arm 6 and with it the arm 2 to close the circuit. A 70 spring 16 may be arranged to resiliently connect the lever 8 with a fixed part and cooperate with the arm 6 to press the star wheel into engagement with the power roller.

75 It will be understood that although only one lever 8 has been described, any suitable number thereof may be employed, one corresponding to each remote operation to be controlled, and each provided with a star wheel and arranged to control a switch, as shown 80 in Fig. 4. Means are provided for selectively controlling the engagement of the star wheels with the power roller. Said means comprises a perforated master sheet 17 arranged on the power driven roller between said roller and the star wheels, so that two of the arms or rays of the star wheels engage the sheet and ride thereon out of engagement with the roller. When, however, a perforation of the sheet encounters an arm of one of the star 85 90 95 100

wheels, the arm projects through the perforation into engagement with the roller and the star wheel is rotated to operate the lever and close the corresponding switch.

- 5 Certain controlled operations require an appreciable period of time for their performance. It is, therefore, desirable to provide means for maintaining certain of the circuits which control such operations closed for an 10 appreciable period of time. To this end, star wheels 21, such as shown in Figs. 2 and 3 of the drawing, having their arms 22 arranged alternately in pairs at greater and lesser distances apart, are provided for operating the 15 switches which control such operations. Two perforations are provided in the master sheet for operating each of the star wheels 21, the first to move it from the Fig. 2 to the Fig. 3 position to close the switch, and the 20 second to move it again from the Fig. 3 to the Fig. 2 position to open the switch. The distance between said perforations in the master sheet determines the interval of time during which the circuit is closed.
- 25 By the arrangement described, matter to be transmitted and frequently repeated may be provided in a master sheet and automatically transmitted by arranging the sheet on the power driven roller.
- 30 Although only one embodiment of the invention is described herein, it will be understood that this application is intended to cover such changes or modifications as come within the spirit of the invention or scope of 35 the following claims.

I claim:

1. A remote control device comprising an electric switch, a power driven roller, a star wheel cooperating with said roller for operating said switch, and a perforated master sheet on said roller for controlling the operation of said star wheel.
- 40 2. A remote control device comprising an electric switch, a lever operatively associated with said switch, a power driven roller, a star wheel rotatably mounted on said lever and arranged to engage the power driven roller to be actuated thereby to operate said switch, and a perforated master sheet on said roller for controlling the operation of the star wheel.
- 45 3. A remote control device comprising an electric switch, power operated means for closing said switch and maintaining it closed during an appreciable interval of time, said means comprising a power driven roller, a lever for operating said switch, a perforated sheet on said roller, and a star wheel on said lever arranged to ride on said sheet and movable from a position in which the switch is open to a position in which the switch is closed, and adapted to engage the roller through perforations in the sheet to be rotated thereby from one position to the other.
- 50 4. A remote control device comprising a

switch, a power driven roller, a perforated master sheet on said roller, a star wheel having arms arranged alternately in pairs and engaging said sheet by one or another pair of said arms, means on said roller for turning said star wheel to engage its next succeeding pair of arms with the sheet to operate the switch when one of its arms engages a perforation in the master sheet.

5. A remote control device comprising a 75 switch, a power driven roller, a lever for operating said switch, a perforated master sheet on said roller, a star wheel on said lever, and arms on said star wheel arranged in pairs, the arms of adjacent pairs being spaced 80 different distances apart, one pair being adapted to ride on the perforated sheet and maintain the lever in a position in which the switch is open and the adjacent pair being adapted to maintain the lever in a position in 85 which the switch is closed, said arms being adapted to engage the roller through perforations in the sheet to turn the star wheel to move one pair of arms out of engagement with the sheet and the adjacent pair into 90 engagement therewith.

In witness whereof, I have hereunto signed my name.

RUSSELL G. THOMPSON.
